UNITED STATES PATENT OFFICE.

WILLIAM H. BANZETT, OF BERGENFIELD, NEW JERSEY, ASSIGNOR TO MERCANTILE CORPORATION, OF DAYTON, OHIO, A CORPORATION OF NEW YORK.

MACHINE FOR MAKING PERFECTED WINDOW-ENVELOP BLANKS.

1,289,084.

Specification of Letters Patent. Patented Dec. 31, 1918.

Application filed February 15, 1916. Serial No. 78,377.

To all whom it may concern:

Be it known that I, WILLIAM H. BANZETT, a citizen of the United States, residing at Bergenfield, in the county of Bergen and 5 State of New Jersey, have invented certain new and useful Improvements in Machines for Making Perfected Window-Envelop Blanks, of which the following is a full, clear, and exact description.

10 This invention relates to certain improvements in machines for making window envelop blanks. This machine is of the type shown and claimed generically in my Patent No. 1,201,430, issued Oct. 17, 1916. In my 15 improved machine, means are provided for embossing a stamp such as used in Government stamped envelopes, imprinting a corner card, cutting a window and thereafter severing the web into rhomb shaped blanks.

20 The whole operation is rotary and continuous, thus permitting speed and cheapness of operation. In the machine, which is the subject matter of this application, certain cutter improvements are embodied. The im- 25 proved cutters permit an adjustment and setting of the cutters as will be more fully pointed out hereafter.

In the drawings—

Figure 1 shows an assembly view of the 30 complete machine.

Fig. 2 shows a diagrammatic view illustrating the several steps in making an envelop blank in my improved machine.

Fig. 3 is an assembly view of the cutters 35 used for making the side and mid cuts.

Fig. 4 is a central sectional view of the same cutters.

Fig. 5 is a top plan view of the cutters shown in Fig. 3.

40 Fig. 6 is a detail view of the cutters, shown in Fig. 3, which are used for making the mid cuts.

Fig. 7 is a detail sectional view of the mid cutter showing the details of the ad- 45 justing devices.

Fig. 8 is a plan view of the window cutter.

Fig. 9 is a section view of the window cutter taken on line 9—9 of Fig. 8 and look- 50 ing in the direction of the arrow.

Fig. 10 is a top plan view of one of the side cutters.

Fig. 11 is a perspective view of one of

the cutters used for making the transverse cuts in the web between the side and the mid 55 cuts.

Fig. 12 is a detail sectional view of the cutter shown on Fig. 11, taken on line 12 and looking in the direction of the arrow.

Fig. 13 is an end view of the rolls and 60 the cutters carried thereby as shown in perspective in Fig. 11.

Fig. 14 is a detail view of the corner card printing roll and the skewed type slug carried thereby. 65

The sequence of operation may be easily traced by referring to the diagrammatic view shown in Fig. 2. The web 20, as it advances, first has imprinted thereon printed legends to form a corner card at I. There- 70 after, at the next step, a stamp is embossed and printed upon the web as shown at II. The web then passes through the window cutter which cuts a window aperture in the web at III. The corner card type lines, the stamp and the window are all at an angle to the side of the web and are parallel to the major axis line of the blank. The blank is in the shape of a parallelogram of rhomb shape having sides parallel with the path 75 of the web from which it is formed. The steps for forming this blank will now be explained. Side cuts, as shown at IV, are first made in the web. Thereafter, at the next station, mid cuts V and deep side cuts 80 VI are made. At the next station, trans- 85 verse cuts VII are made, these cuts extend diagonally and connect the deep side cuts VI and the mid cut V. The blank is now complete and by means of speeding up rolls, 90 is separated from the web as shown at VIII. The blank then advances to blank receiving and delivery mechanism. The blank thus formed is produced in the most economical 95 manner from a web of paper, and paper waste is reduced to a minimum.

The machine for carrying out the above steps will now be explained.

The paper web 20, passes from supply roll 100 21, under an idler roll. The web passes di- rectly upwardly between the impression platen 22 and the corner card printing roll 23. This roll carries printing plates 24 which are arranged in skewed relation on roll 23 as shown in Fig. 14. The plates are 105 inked by the inking rolls D, which are adapt-

ed to take ink from the ink fountain by means of a ductor roll operating in the well known manner. In order to lift the type from the web when the machine is stationary, the ink rolls and the type carrying rolls are mounted upon a frame 25, which frame is pivoted to the machine frame and which is adapted to be swung back by means of the handle and eccentric device shown at 26. 5 The above instrumentalities are adapted to print the printed legends on the web which form corner cards as shown at I in Fig. 2.

Stamp embossing.

15 Suitably journaled on the machine frame is a printing and embossing cylinder 27 carrying four embossing dies 28 which are adapted to coact with matrix dies 29 on cylinder 30. The dies 28 are adapted to receive 20 ink from inking rolls D² taking ink from a fountain by means of the usual ductor roll D³. The ink rolls and fountain are mounted upon a pivoted frame which can be lifted by the eccentric device 31. The stamp embossing device embosses and prints a stamp on the web as shown at II, Fig. 2. The reading line of the stamp, is embossed and printed upon the web in parallelism with the reading line of the printed legends forming the 25 corner card at I. After passing through the stamp embossing device, the web passes between feeding rolls 32 and 33 the latter roll being spring pressed into engagement with roll 32.

35

Window cutting device.

To cut the window, shown at III, in the web, the web is passed between a window cutter roll 34, carrying two window cutters 40 thereon, as shown in Fig. 8. The details of these cutters will be described in detail later. Coacting with the cutters is a die roll 35 which die roll carries pins at 36, which remove the window chips from the cutter. 45 Strippers, as 37, strip the chips from the pins and allow them to fall upon a conveyor belt 38 which carries them to a suitable box at the side of the machine.

50

Side cutting devices.

To make the side cuts IV, the web passes between cutter roll 39, which carries knife cutters 40, secured to flattened spots 41 on the roll 39 by screws and dowels as shown in 55 Fig. 10. The top of the cutter knives extend slightly beyond the periphery of the roll 39, as shown in Fig. 1, and coact with a hardened die roll 42 having chip removing pins and stripper blades. After the chips are removed from the roll 42, they fall into a box from which they are removed by air suction through pipe 43. It will be understood that there are two cutter knives 40 on the same roll 39. These knives are mounted upon the 60 opposite ends of the roll and angularly dis-

posed with respect to each other in order to cut the side cuts at opposite sides of the web as shown at IV in Fig. 2.

After leaving rolls 39 and 42 the web passes between web feeding rolls 44 and 45, 70 the latter being spring pressed into contact with the web and the coöperating roll beneath.

Mid and side cutter device.

To cut the mid cuts V and the side cuts 75 VI the web passes between a cutter head shown at 46 which carries a plurality of cutters which coact with die roll 47 having chip removing pins and stripper blades. There is one pin for each side cutter and one for the mid cutter as shown in Fig. 3. The chips fall into a box and are removed by suction through a branch pipe leading to pipe 43. The cutter head will be more fully described hereafter.

Leaving the cutter, which makes the cuts V and VI, the transverse cuts VII are made by cutter 48 coacting with die roll 49. Thereafter the blank passes between feeding rolls 51 which speed up the blank slightly to space it from the succeeding blanks as shown at VIII in Fig. 2. After the blanks leave the speeding up rolls, they are delivered to the right and left into storage troughs by means of vibrating blades 53 which are rocked by a link connected to some operating part of the machine, as a crank pin on the gear driving the cutter head 46.

Gearing train.

100 All of the cutter rolls, die rolls, feeding rolls, embossing and printer rolls are geared together by gearing shown by dotted circles in Fig. 1. These gears need not be mentioned in detail. It is sufficient to state that power is received from a driving pulley at 56 and that the intermediate gearing drives all the parts in unison and in this way the printing, cutting, and embossing are properly spaced and coördinated on the web.

105 The web feeding rolls 33 and 32, 44 and 45, 54, 55 are adapted to maintain the web taut and in tension at all points in the machine.

Mid and side cutter.

110 The details of the cutter which makes cuts V and VI, will be first described, as certain of its principles and construction is similar to the other cutters.

115 In Fig. 3, 70 is a shaft which is suitably journaled in the machine frame and which carries on one end a driving gear. The shaft 70 is prevented from endwise movement in the frame by suitable collars. Strung on the 120 shaft are a number of cutter bodies. There are three of these bodies, i. e. 71, 72 and 73. The center body 72, carries the cutters which make the mid cuts V, and the outer bodies 71 and 73 carry the cutters which make the side 125 130

cuts VI. Each of the cutter bodies are slotted as shown at 74 in Fig. 4 and provided with clamping means as 75, whereby the cutter body may be clamped to the arbor 70 after it is properly positioned thereon. It will be understood that each cutter body is similarly slotted and similarly clamped.

In making cuts at different parts of the web, as shown at V and VI, in Fig. 2, it is important that the cuts be accurately placed, otherwise the finished blank will be defective. I accordingly provide means for angularly shifting each of the bodies 71, 72 or 73 around the carrying shaft 70, forward or back, relative to each other. This adjustment means is shown for the center body 72 only, but a similar adjustment is provided for the bodies 71 and 73. Referring to Fig. 4, two adjusting screws 76 and 77 are threaded into the cutter bodies and are adapted at their inner ends to abut against flat spots on the shaft 70. When it is desired to adjust the bodies angularly with respect to one or both of the other cutter bodies, the clamping means 75 is loosened. Thereafter one adjusting screw, for example 76, is loosened and the other, say 77, is tightened. In this way the cutter body can be very accurately adjusted on the shaft. When the adjustment is correct, the clamping means 75 is again tightened and the body will then remain in the proper angular relation to the carrying shaft. I also find it desirable to adjust the lateral position of the cutter bodies on the shaft 70. This is done by threading portions of the shaft and providing clamping nuts 78 and 79 which are adapted to be tightened against cutter bodies 71 and 73 respectively. By loosening one nut and tightening the other, the cutter bodies may be set to any desired position on the shaft. If desired to space the cutter bodies farther apart, paper or fiber shims may be placed between 71 and 72 and between 72 and 73. It will be understood that although three blocks or bodies are shown that any number of these bodies may be mounted upon the carrying shaft.

Cutter blades and supporting structure.

The cutter body 72, has a flat face 80 and a tapered face 80^a. (In the present embodiment there are two of these faces, one flat and the other tapered, but there may be one or more of such flattened faces or one or more of the tapered faces depending upon the diameter of the cutter body and the gear ratio of the driving gear.) The flattened face 80 and the base line of tapered face 80^a are parallel to each other and normal to a vertical line passing through the center of shaft 70.

The flattened face 80 is provided with a plurality of cupped depressions to receive springs 81. These springs press outwardly upon the bottom of a subbase plate 82,

which plate is guided between cheek plates 83 which are secured by screws to the cutter block or, if desired, the cheek plates may be integral with the body. In order to limit the outward movement of the subbase plate, 70 limiting cap screws 84 are used. These screws are threaded into the cutter base block and pass loosely through the subbase plate. The heads of the screws engage the plate and thereby allow an inward movement of the plate but limit the extent of the outward movement which is imparted thereto by the springs 81. Locking set screws 85 are provided to lock the limiting screws in position after they are once adjusted. 80

At the top of Fig. 7, a modified construction is shown. In this modification the face of the cutter block is tapered at 80^a. Interposed between the subbase plate 82 and the tapered face 80^a of the cutter block is a 85 wedge 86 having a lower taper to correspond with taper 80^a. The same cheek plates 83 are provided to bear against the sides of the subbase plate 82. Similar limiting screws 84 and locking set screws 87 are 90 employed at each side of the wedge plate to adjust the base plate to and from the cutter base block.

It will be understood that the wedge arrangement or the spring arrangement for 95 forcing the subbase plate outwardly in this machine are modifications. Either construction may be used.

The knives carried by the subbase plates 82 both top and bottom are alike. The contour of the two parts 88 and 89 are shown in Figs. 4, 6 and 7. The knives have a flat base to seat on the base plate and are firmly secured thereto by screws. The shape of each knife is determined by the shape of the 100 cut to be made and by referring to Figs. 4 and 6 it will be seen that each knife, has an outwardly tapering portion 90 which tapers from the periphery to the base of the knife and a straight inner face 91 which extends 105 downwardly in a direction perpendicular to the face of the base plate 82. The tips of the blades are so shaped that all points of the tip are equidistant from the center axis of the cutter block. The two knives 88 and 89 are arranged with the perpendicular straight edges in close contact as shown in 110 Fig. 6.

The knives for making the side cuts VI are similarly mounted upon base plates and 120 the base plates are mounted in the same manner as heretofore described, i. e. either by wedges or with the spring backing. The knives themselves i. e. 92, 93 and 94, 95 are in two parts and are constructed in a similar 125 manner to knives 88 and 89. They have one tapered and one perpendicular edge. The purpose of this construction will be hereafter pointed out.

The relative arrangement of the knives 130

carried on cutter heads 71, 72 and 73 can be seen by referring to Fig. 5 which shows that the cutter blocks are spirally disposed about the arbor 70. The disposition of the cutter 5 base blocks is such that on rotating, the cutters will make the cuts V and VI in a diagonal transverse line in the web as shown in Fig. 2. This Fig. 5 also points out the desirability of adjusting the cutter base 10 blocks by the adjusting screws 76 and 77, see Fig. 4. This adjustment is of course necessary to set the knives so that they are alined with a spiral.

15 *Die roll.*

Coacting with the knives is a hardened die roll 47, this roll being mounted upon an arbor 101 which arbor is mounted in bearing blocks 102 and which carries at one end a 20 driving gear which intermeshes with the driving gear on the cutter shaft. The die roll 47 is urged toward the cutter head by springs 103 which underlie the bearing blocks. To limit the extent which the die 25 roll can approach the cutters an adjusting means consisting of screws and nuts 104 is provided. The adjusting devices bear at one end on the machine frame and at the other on the bearings 102. By setting these 30 adjustment devices the die roll 47 can be permitted to approach the cutter but at the same time excessive pressure between the cutter and die roll is prevented. Excessive pressure of course would damage the knives. 35 A similar spring bearing and adjustment is provided for each of the die rolls 35, 42, and 49 shown in Fig. 1.

40 *Knife operation.*

40 In operating the machine the die rolls are adjusted so that they just about contact with the tips of the blades. The paper web on passing between the knives and die roll will be cut, but the knives and die roll will be 45 uninjured since they are held from actual damaging contact by the adjusting devices 104. The spring pressed rolls also permit heavy or excessively thick or patched sections of web to pass through the machine 50 without breakage.

When the knives wear or become nicked it is necessary that they be sharpened. This is done by releasing the limiting screws 84, after which the springs 81 are effective to 55 throw the subbase plates outwardly. Or if the wedge construction is used the wedge is set up to force the subbase plate 82 outwardly. The tips of the knives are then ground down by a suitable grinder until the 60 diameter of the ground portion is reduced to the original diameter before the limiting screws were released. The tapered surfaces 90 of the knives are then whetted to bring the cutting edge to a line. It will be understood that after the limiting screws 84 have

been moved to permit the subbase plate to come out they will be locked by set screws 85. By reason of the perpendicular face 91 of the knives their shape is maintained even after many sharpenings.

I am aware that it is old to provide knives with spring backing and I do not claim that as my invention. In previous constructions the springs have been placed directly under the knives and where a double knife construction is utilized the knives are likely to work apart and cause inaccurate work. In my construction the attachment of the knives to the subbase plates and the cheek plates to guide the subbase, avoid the disadvantages and defects of prior constructions.

70 80 85 90 95 100 105 110 115 120 125 130 *Severing cutter.*

The cutter which makes the transverse severing cut is shown in Figs. 11, 12 and 13. The cylinder 48 is slotted as shown in Fig. 11. The base of this slot is shown at 110 and the sides of the slot at 111, and 112. The cylinder is also slotted on its opposite side as shown by the dotted base line 113, in Fig. 13. The bottoms of these slots have depressions in which a number of springs 114 are placed. The springs force outwardly against the bottom of a knife carrying cage 115 which cage has side portions 116 and 117 to coact with the sides 111 and 112. Limiting screws 118 are utilized to limit the extreme outward movement of the cage. The knife 119 is provided with bearing blocks 120 at each end and with a tapered face 121. Wedge blocks 122 coact with the tapered side of the knife and are fastened by means of screws to the bottom of the cage. This knife therefore may be given two adjustments—one by loosening the limiting screws 118 and thus permitting the cage to come out prior to sharpening the edge of the knife. The other adjustment is made by loosening the wedge block 122 and packing up between the bearing blocks 120 and side 117 of the knife cage. This adjustment permits the knife to be slightly twisted to bring the ends into proper alignment with the previously made cuts V and VI in the web. It will be understood that the parts shown in Fig. 11 are duplicated on the rear side of roll 48 as will appear from Fig. 13 which shows two knives 119 angularly displaced with respect to each other.

In order to prevent the knife 119 from shifting endwise in the cage when the wedge blocks 122 are released, dowel pins 123 are placed in the base of the cage at each end of the knife.

It will be understood that the adjustment for twisting the knife by placing shims between bearing blocks 120 and side 117 of the cage is a close adjustment and that if a

greater adjustment is desired the cutter bodies on the other cutter head —46— are adjusted. It will also be understood that the tip of the knife 119 is at all points equidistant from the center axis of the knife carrier and projects slightly beyond the periphery of the roll 48. The tops of the side walls 116 and 117 of the cage are also slightly below the periphery of roll 48.

10 I am aware that it is old to mount a severing knife with spring backing and that such knives have been twisted for adjustment and I do not claim these features broadly but merely the specific embodiment here shown 15 and described.

The adjustments of the cutter which cuts the side cuts IV is made by packing up between the lower face of the base of the knife 40 and the flat face 41 of cutter roll 39. The 20 knife has a tapered face 90 and a perpendicular face 91 similar to the other knives.

Window cutter.

Cylinder 34 carries two diametrically opposite window cutters which make the windows III. These cutters comprise two U-shaped knives 130 and 131 which are seated upon oblique flat faces upon the cylinder. These faces are made by making two mill 30 cuts in the cylinder. The direction of these cuts is oblique to the axis of the cylinder and the bases 132 and 133 of the cuts are both normal to a plane which intersects the median line of the cutter. This plane is indicated by the dotted line in Fig. 9. Each knife 130 and 131 has a flat base 134 which seats against the flat face of the cuts and are secured thereto by screws. Each knife has a tapered inner edge 136 and a straight outer edge 137 which is perpendicular to the base 132 or 133. Knife 130 also has an extending portion 138 which has a straight inner face which registers with the straight face of the other knife and an outwardly tapered face. 40 The portion 138 extends past the end of the knife 131 as will be clearly seen in Fig. 8. Knife 131 has a similarly extending part 139 which extends past the end of the knife 130. By reason of these extending portions 45 138 and 139, it is possible to place shims under the knife bases when it is desired to sharpen the knives. When the knives are so raised, there is a telescoping action between the two U-shaped knives, and the extensions permit this telescoping action without a separation between the ends of the knives.

It will be understood that my invention is not limited to the precise form and construction described and shown, but is susceptible to various modifications which would be devised by those skilled in the art.

What I claim as my invention is more particularly pointed out in the appended 55 claims.

I claim:

1. In an envelop blank machine; in combination; with means for continuously advancing a web of paper; means for cutting in said web a plurality of window apertures, having the major sides of the window in parallelism with the major axis of a to be formed blank, said axis being disposed at an angle to the side of the web; coacting rotary means for cutting side cuts in the web; coacting rotary means for cutting diagonally disposed side and mid cuts in the web; coacting rotary means for diagonally severing the web between the side and mid cuts and thereby forming a completed rhomb shaped window envelop blank; and means for adjusting and coördinating the operations of said cutter means whereby the cuts are properly registered one with the other upon the moving web. 75

2. In a machine of the class described, in combination; means for continuously advancing a web of a paper; coacting rotary means for cutting side cuts in the web; a cutter having a plurality of independently mounted cutters thereon, means for varying the angular relation of said cutters with respect to each other, whereby adjustments in the location of the cuts in the web, made by the said cutters, may be made, and coacting rotary cutter means for severing the said web with diagonal cuts whereby the web is formed into rhomb shaped blanks having their major axis at an angle to the side of the web. 95

3. In a machine of the class described, in combination, means for continuously advancing a web of paper; coacting rotary means for cutting in the said web a plurality of window apertures, a cutter arbor; 105 a plurality of independent cutter bodies thereon; knives on said bodies, spirally disposed with respect to each other, a die roll coöperating with said knives whereby upon rotation of the knives and die roll a plurality of diagonally disposed cuts are made in moving web, and means for adjusting the angular relation of the cutter bodies on the arbor whereby the position of the cuts in the web may be varied. 110

4. In a machine of the class described, in combination, a means for continually feeding a web of paper; an arbor adjacent said web; a plurality of cutter bodies on said arbor, independent adjusting means for said cutter bodies whereby they may be given a relative angular adjustment with respect to each other and to the said arbor, a plurality of knives on said cutter bodies said knives being spirally disposed to each other and a die roll for coöperating with the knives and making diagonally disposed cuts in the web. 120

5. In a device of the class described, in combination, a cutter head having a plurality of flat faces thereon, cheek plates se- 130

6
cured to the said cutter head, subbase plates guided between said cheek plates, springs intermediate the cutter head and the subbase plates adapted to force the subbase plate outwardly, limiting screws to limit the aforesaid outward movement and knives rigidly secured to the subbase plate, said knives having their periphery at all points equidistant from the axis of the cutter head.

10 6. In a device of the class described, in combination, a cutter head having a plurality of independent cutter bodies thereon, each of said bodies having flat faces, cheek plates at the sides of the said flat faces, subbase plates between the said cheek plates, means for forcing the subbase plates, outwardly, limiting screws to limit the aforesaid outward movement; knives rigidly carried on the subbase plates said knives having all points of their periphery equidistant from the axis of the cutter head, and means for adjusting the cutter bodies relatively to one another whereby the angular position of the knives on the cutter head may be 25 adjusted.

7. In a machine of the class described, in combination, a rotary cutter head having a plurality of independent cutter bodies, a plurality of cheek plates secured to said cutter bodies, a plurality of subbase plates guided between the aforesaid cheek plates, means for forcing the subbase plates outwardly, a plurality of knives rigidly mounted on each of the subbase plates said knives having all points of their periphery equidistant from the axis of the cutter head and means for shifting the cutter bodies relatively to one another whereby the position

of the knives may be angularly adjusted on the cutter head.

8. In a machine of the class described, in combination, a rotary cutter head having a body portion which is provided with a plurality of faces upon which the cutting elements are to be supported a plurality of 45 cheek plates extending from the body of the cutter, subbase plates guided between the aforesaid cheek plates, means for forcing the subbase plate outwardly, limiting screws to limit the outward movement of the said 50 subbase plates, knives rigidly secured to the subbase plates having their cutting periphery at all points equidistant from the axis of the cutter head, and a rotary die roll to coöperate with the aforesaid knives whereby a paper web passing therebetween is cut.

9. In a machine of the class described, comprising in combination means for continuously advancing a web of paper, means for cutting in said web a plurality of apertures skewed relatively to the longitudinal dimension of the web; means for severing the web at an angle between the apertures and thereby forming a plurality of rhomb shaped envelop blanks; and means for adjusting and for coöordinating the operation of the said feeding, aperture cutting, and severing devices whereby the apertures are properly spaced in the blanks.

In testimony whereof I affix my signature 70 in the presence of two subscribing witnesses.

WILLIAM H. BANZETT.
